PRINTING PLATE AND METHOD OF MOUNTING THE SAME

Arthur B. Davis, Springfield, Ohio

Application June 26, 1931, Serial No. 546,951

4 Claims. (Cl. 101—415.1)

This invention relates to the printing of books, magazines and the like wherein the type is carried on a plate in the form of a thin sheet or shell. More particularly, the invention is concerned with the reinforcement of electrotype shells and to the manner of mounting the same preparatory to actual printing. The present application is a continuation in part of my prior application Serial No. 270,534, filed April 16, 1928.

According to present practice, each electrotype shell formed by depositing copper electrolytically upon a mold taken from an original or master form is reinforced by a heavy non-flexible lead backing which is applied to the back of the shell. In the molten state. The intense heat to which the shell is thus subjected, causes objectionable distortion of the type face. Considerable time and skilled labor must then be expended to work the face back into its original shape with the result that the cost of the finished plate is increased materially and a true reproduction of the original form surface is seldom obtained. With such plates, complicated make-ready sheets are required and the making of the press ready for printing is a tedious process, tying up the costly press equipment for long periods of time.

The printing surfaces of standard lead backed plates stretch considerably in being curved for use on rotary presses thereby making it impossible to make cut overlays from the master form. With some designs, the printing surface becomes distorted to such a degree in bending that it will wear off rapidly in the press.

The above characteristics of standard electro- plates are particularly objectionable in process or multi-color printing owing to the necessity for exact register between the different color plates which become distorted differently in the application of the lead and in bending. It is virtually impossible to match the color of the original owing to the fact that the so called "dots" producing the different half-tone effects are distorted materially in working the lead backed shell into shape.

One object of the present invention is to overcome the above objections by providing a new and improved printing plate assembly which permits of a method of manufacture avoiding distortion of the type surface; which reduces the cost of and the time required for the manufacture of the plate assembly; which simplifies and facilitates the preparation of detail make-readies before going to the press, and may, in some instances, eliminate the use of such make-readies; and which at the same time enables standard

press equipment to be used in the mounting of the plate assembly on the press.

A more detailed object is to provide a printing plate assembly comprising a relatively flexible type-carrying sheet stretched over and attached to a separately formed backing member adapted for adjustment in any direction along the surface of a printing press support.

Another object is to provide in a printing plate assembly of the above character, a type-carrying sheet possessing sufficient flexibility to yield under the normal pressure of printing and whereby added printing pressure over selected areas of the type face may be produced by make-ready details located between the sheet and its backing.

Other objects and advantages of the invention will become apparent from the following detailed description taken in connection with the accompanying drawings, in which

Figure 1 is a fragmentary plan view of the cylinder of a printing press on which is mounted a plate assembly embodying the features of the present invention.

Fig. 2 is an enlarged sectional view taken along the line 2—2 of Fig. 1.

Fig. 3 is a rear elevational view of the plate assembly with a portion of the backing plate broken away to show the detail make-ready employed.

Fig. 4 is a fragmentary sectional view of one side portion of the plate assembly on a still larger scale than Fig. 2.

Fig. 5 is a fragmentary view similar to Fig. 4 illustrating a modification of the present invention.

Fig. 6 is a fragmentary view similar to Fig. 1 showing a further modification of the invention.

Fig. 7 is a section taken along the line 7—7 of Fig. 6.

Fig. 8 is a sectional view similar to Fig. 7 taken through the opposite end of the plate assembly.

In the exemplary form of the invention shown in the drawings, 5 indicates a thin sheet metal shell commonly known as an electrotype having type 4 corresponding to the characters and other configurations of the page to be printed standing out in relief on one side of the shell and presenting faces which contact the paper during printing. Cavities corresponding to such type indent the other or back side of the shell so that at all points the metal of the shell is of substantially uniform thickness usually from .015 to .020 of an inch. Narrow marginal edge portions 6 integral

with the rectangular type-carrying portion are formed along each side edge of the shell.

In accordance with the present invention, the type cavities are completely filled with material 5 which is sufficiently hard and strong to reinforce the type against collapse under the pressure encountered in use on a press, which will adhere well to the metal of the shell without the application of a distorting heat, and yet possesses a 10 substantial degree of flexibility without danger of cracking. In so far as the reinforcement of the type is concerned, it is merely necessary to fill the cavities, but to facilitate the formation of a smooth back surface disposed exactly parallel 15 to the type face of the shell, it is preferred to coat the entire under surface of the shell and thereby form a continuous layer 7^a of a thickness, when finished, approximately equal to that of the shell.

20 Various materials may be used for filling the type cavities and the present invention is not limited to the use of any particular material. I have found that a non-metallic composition comprising powdered wood and an adhesive binder is 25 well suited for this purpose. Preferably this material is applied as a thick paste formed by the addition of a volatile solvent such as acetone to the material as manufactured and sold by the A. S. Boyle Company of Cincinnati, Ohio.

30 With the shell supported face down on a smooth surface, the paste may be pressed readily into the type cavities to insure complete displacement of air therein. The excess is leveled off to form a continuous coating of uniform thickness 35 and having a smooth back surface. The filler is then allowed to set, which takes place rapidly in view of the volatile character of the solvent employed. If desired, an excess amount of the filling material may be applied and the 40 coating ground down to the desired thickness and its surface made exactly parallel to the type face of the shell. Preferably the coating 7^a thus formed extends beyond the edges of the type face proper but the outer part of the marginal edges 45 6 is left uncovered.

The composite type-carrying sheet thus formed is relatively flexible and may be bent to conform to a backing surface of the curvature commonly used in standard printing presses without injuring 50 the filling or distorting the type face. Since the fillings in the type cavities adhere to the shell surface without subjecting the shell to a temperature sufficiently high to cause distortion, the type face is virtually an exact reproduction of 55 that of the original form.

Printing plates constructed as above described may be used in flat bed presses or in presses in which the plates are carried on the convex periphery of a cylinder 8 . To enable the reinforced 60 shell to be securely fastened to cylindrical or flat bed supports of standard construction, the shell is backed by a rectangularly shaped plate 9 preferably made of metal such as steel or brass and of a uniform thickness such that the combined 65 thickness of the coated shell and the backing plate is substantially equal to that of the lead backed shells now generally used. With the shell coated as above described, a plate approximately 70 0.10 of an inch thick would be employed. The plate is preferably made slightly wider than the coating 7^a but less than the width of the shell so that the marginal edges 6 extend beyond edges 75 of the plate. For a reason to later appear, the plate may be made longer than the shell with

other side edges projecting beyond the top and bottom marginal edges of the shell.

The backing plate is preformed to a uniform curvature corresponding to that of the press support upon which it is to be mounted. For use on 5 the rotatable cylinder 8 , the plate would have one concave surface shaped to lie against the cylinder surface. On flat bed presses, flat backing plates would ordinarily be employed.

To avoid wrinkling or other distortion of the 10 coated electrotype under the severe lateral strains to which it is subjected during printing, the present invention contemplates drawing or forcing all of the contacting parts of the filled shell and backing plate together under pressure. This is 15 accomplished by subjecting the shell to edgewise or lateral stress by applying oppositely directed forces to opposite side edges of the shell, the line of action of the forces being the same as the direction of movement of the shell when supported 20 in the press. When used on a cylinder as shown in the drawings, the shell is placed under tension and thereby stretched over the convex surface of the backing plate 9 . The shell is thus held 25 taut and the under surface of the coating 7^a is maintained in firm contact with the plate.

The means employed in thus stretching the shell on the backing plate may, as in the present instance, also serve to detachably secure the type sheet and the plate 9 together to form a unitary 30 structure hereinafter called the printing plate assembly. Herein, this means comprises a pair of fastening elements in the form of flanges 10 formed along two opposite side edges of the shell on the rear side thereof. These flanges may be 35 formed from the metal of two of the marginal edge portions 6 by bending the outermost part of these portions backwardly around a suitable fixture plate (not shown) and then reversely and toward each other to form two opposed grooves 40 conforming in shape to that of the opposite side edges of the backing plate 9 which constitute fastening devices engaging the fastening elements 10 when the plate and shell are assembled. The upper corners of the backing plate edges are 45 rounded slightly as indicated at 11 (Fig. 4) to form a gradual bend in the portions 6 in order that the stretching forces applied will produce a maximum degree of tension in the shell with a minimum distortion of the metal. The lower 50 corners 11^a along the edges of the backing plate are made relatively square to minimize the tendency of the flanges to straighten out under the lateral tension to which the shell is subjected. In order to permit the back surface of the plate 9 55 to lie in contact with the surface of the cylinder, the flanges are seated in narrow grooves 12^a formed along the edges of the plate on the underside thereof.

Preferably the free edges of the flanges 10 are 60 stiffened which may be accomplished simply and effectually by corrugating the flanges by forming a series of closely spaced indentations 12 along their free edges.

One way of deriving the force for stretching 65 the shell as above described is by the action of the backing plate 9 or a part thereof as a wedge when assembled with the filled shell. For this purpose, the plate, in the embodiment of the invention shown in Figs. 1 to 4, is constructed 70 with surfaces which are inclined relative to the longitudinal side edges of the shell and which, when all or part of the plate is shifted longitudinally of the shell, cause the effective width of the plate to be varied. If this shifting takes 75

place with the plate lying against the filled surface of the shell, an outward pressure will be exerted on the flanges 10 thereby spreading the flanges apart and stretching the shell over the 5 backing plate. In order that the plate 9 may have parallel side edges, it is made in a plurality of separate parts adapted to be assembled in abutting edge to edge relation at joints which are located intermediate the side edges of the plate 10 and whose engaging surfaces form the wedges.

It is preferred to employ a backing plate composed of two parts indicated as 9 and 9^a in Fig. 3 which are substantially triangular in shape and, in the present instance, are right angle trapeziums united at a tongue and groove joint 13 which extends substantially diagonally of the backing plate. With the joint 13 inclined at this angle, the tendency of the two parts to buckle at the joint, under the tension to which the shell 20 is subjected, is virtually eliminated inasmuch as this buckling tends to take place along a longitudinal line of the backing plate. The tongue and groove connection 13 effectually holds the two parts in edgewise relation and yet permits 25 the parts to be shifted relative to each other. Preferably the parts 9 and 9^a are made of such length that their edges 14 project beyond the top and bottom or unflanged edges of the shell and are thus readily accessible for expansion or contraction of the shell.

It will be apparent that the rectangular plate formed as above described may, by lengthening the plate, be reduced to a width where the plate will drop in between the flanges 10 and become 35 aligned with the grooves defined thereby. By forcing the ends 14 into the shell from opposite ends thereof, the plate is contracted longitudinally but expanded laterally, the side edges entering the grooves and eventually engaging the 40 flanges 10. Further application of pressure to the edges 14 stretches the shell tightly over the backing plate which is usually applied by driving the triangular parts of the backing plate into the shell after the plate assembly has been 45 mounted on the press cylinder. Preferably the inclination of the joint 13 relative to the longitudinal center line of the plate that the friction developed when the shell is stretched over the backing plate will retain assembled relation of 50 the plate and shell and prevent longitudinal shifting of the parts 9 and 9^a. When the shell and backing plate are assembled, it will be apparent that they may be detached conveniently simply by pulling the ends 14 apart.

With the filled shell and the backing plate 55 secured together in the manner above described, it will be apparent that a substantially rigid plate assembly is formed which, in thickness and general shape, closely approximates that of standard lead backed electrotypes. The plate assembly may therefore be secured to a printing cylinder by the use of clamping devices of standard construction. As shown in Figs. 1 and 2, these clamping devices generally comprise a block 60 65 15 bearing along one edge on the cylinder surface. The opposite edge has a lip 16 overlying the upper surface of the marginal portions 6 of the shell and bearing against the same opposite the rounded edge 11 of the backing plate. The 70 clamping action is obtained by tightening a screw 17 threading into a block 18 seated in an undercut groove 19 extending spirally around the cylinder. Several of these clamping devices may be applied to the beveled projecting edges 14 of 75 the backing plate so as to press the intermediate

portion of the plate assembly firmly against the supporting surface and avoid any buckling tendency. Inasmuch as the shell is stretched over the backing plate in the direction of motion of the shell when mounted on the press cylinder, 5 it is not necessary that the clamping devices at the top and bottom of the page overlie the corresponding marginal edges of the shell.

After the plate assembly has been placed in proper position on the press cylinder and before 10 the clamping devices have been fully tightened down, the plates 9 and 9^a are driven into the shell so as to produce the desired degree of tension in the shell. Then when the clamps are tightened, 15 all of the edges of the plate assembly will be 20 pressed firmly against the upper surface of the cylinder and the assembly securely held in place. The stiffening of the free edges of the flanges resulting from the formation of the transverse indentations 12 overcomes any tendency of the 25 flanges to straighten out or pull through between the cylinder and the edge 11^a of the backing plate when the latter is expanded. The abrupt edge 11^a which engages the flanges 10 behind the indentations 12 also assists in overcoming the 25 tendency of the flanges to straighten out under tension.

With the foregoing method of reinforcing and mounting the shell, it will be apparent that the subjection of the shell to a distorting temperature is completely eliminated and that the reinforced shell is so flexible that it can be bent to the proper curvature without distortion of the type face. Therefore, the latter is a true reproduction of the original form. Such a high degree 35 of accuracy in reproduction is particularly desirable in multi-color printing where one shell must be made for each basic color used and where proper blending requires that the different color impressions be superimposed upon each 40 other in perfect register. Since the present invention enables a plurality of true reproductions of the original form to be made, this requirement is satisfied with a minimum expenditure of time and labor both in the preparation 45 of the shells and in the mounting thereof in the press.

Moreover, the original size and shape of the "dots" which are formed in relief on the type 50 faces to produce the half-tone or shaded effect are effectively preserved. This is because the shell is not subjected to hammering or other distorting forces as is commonly done in present practice in order to work the shell surface back into its original shape after application of the 55 lead backing.

The high degree of accuracy obtained with the present process is also advantageous in that it eliminates, in some instances, the necessity for detail make-readies which are commonly employed for removing imperfections in the type 60 face and for bringing out the "solids". Where such make-readies are required, their complexity, that is the number of make-ready details or spots required to be pasted onto the make-ready sheet, is reduced to a minimum and the make-ready accordingly simplified.

With the type cavities filled as above described, the inherent flexibility of the shell is preserved to a substantial degree, at least to an extent which enables the reinforced shell to respond under normal printing pressure to the detail make-ready placed directly beneath the filling material. The make-ready is in the form of a paper sheet 20 bearing the usual details or 75

patches 21 pasted to the sheet in positions opposite those portions of the type face which are to be raised. Preferably, the sheet 20 is a proof taken from the type face in a special proving press while the shell is secured to a temporary backing plate, and the patches 21 may be cut from other proofs and pasted to the sheet 20 over the parts of the sheet corresponding to those of the printing surface to be raised.

10 While the detail make-ready may be prepared as a separate detached sheet, proper location of the original make-ready patches or those additions that may occasionally be required to be made in the press room may be greatly facilitated by securing the proof sheet 20 to the surface of the coating 7^a, as by the use of paste, with the printed parts of the proof in register with the corresponding parts of the type face. Then, to raise a particular part of the type face 15 so as to cause the desired added pressure to be applied during printing, it is merely necessary to paste a patch of the proper thickness over the corresponding part of the proof sheet. The detail make-ready thus becomes a permanent 20 part of the reinforced shell and may be stored and preserved with the shell for the printing of future issues of the book or other publication. The relation of the type face and make-ready being thus established, there is no danger of 25 slippage between the two after the plate assembly has once been mounted in the press.

By providing a reinforcement for the shell which enables the detail make-ready to be mounted directly beneath the shell instead of on 30 the impression cylinder as is necessary in present practice, the preparation of the make-ready is greatly facilitated, the size of the packing cylinder is kept equal to the plate cylinder, and in addition the time required in making of the press 35 ready for printing is materially reduced. During preparation of the make-ready sheet, the filled shell may, owing to its flexibility, be proved while supported on a surface of a different curvature from that on which it will ultimately be 40 used in actual printing. The preparation of the make-ready sheet and the location thereof with respect to the shell may therefore be carried on in advance of going to the press without tying up the costly press equipment as is now done in present 45 practice and the make-ready may be prepared in a separate department by specially trained workmen. The present method of preparing the make-ready is also facilitated by the provision, in the present construction, for ready detachment 50 of the shell from the backing plate and remounting of the plate assembly which ordinarily must be repeated several times in the course of preparing the make-ready. With the make-ready thus mounted, shifting of the plate assembly for final 55 register or line-up does not require opening of the packing cylinder for shifting the make-ready to correspond with the shift of the plate.

In certain types of presses, it is customary to emphasize certain parts of the lead backed shells 60 now used by pressing the same under hydraulic pressure between an "underlay" and an "overlay". The necessity for thus treating the shell is completely eliminated by the present invention because the filled shell is so flexible that it will 65 respond to an underlay placed beneath the shell. Furthermore, the underlays may be corrected quickly and conveniently.

As used in the appended claims, the expression "make-ready details" is intended to refer to 70 those paper patches or spacing elements which

are used in productive printing on machine finished or uncoated paper for the purpose of emphasizing selected and well defined areas of so-called "solids" and relieving the "high lights" under pressure normally applied during printing, 5 such patches having heretofore been mounted on the impression member of the printing press so as to constitute a so-called overlay.

Fig. 5 illustrates a modification of the present invention in which the shell 5 and the backing 10 plate 9 are not assembled as a unitary plate as in the preferred form above described. In this modification, the backing plate may be a single sheet of metal and the marginal edges of the filled shell formed with ribs 22 along their upper 15 edges, preferably from the metal of the marginal edges 6. The clamping devices 23 employed are formed with hooked ends 24 adapted to engage behind the ribs 22 and apply the stretching forces to the shell when the clamps are tightened down. 20 To enable this action to be obtained, the shell is made of such width relative to the backing plate that the ribbed edges will not contact the surface of the supporting cylinder until the clamps have been applied and tightened down. 25

Figs. 6, 7, and 8 illustrate still another method of securing the shell, when reinforced in the manner previously described, to the backing plate and securing the plate assembly to the press cylinder. In this modification, the backing plate, 30 numbered 25, is an integral sheet with grooves 26 formed along two opposite side edges and lugs 27 formed at the other edges to receive screws 28 by which the plate is clamped in place on the press cylinder 8. The marginal edges of the shell 35 to which the stretching force is to be applied are formed with tongues 29 adapted to enter slots 30 in narrow bars 31 which are then turned through a revolution or more and the uncoated edge portions of the shell thus wrapped around and secured to the bars. At their opposite ends, the bars are formed with lugs 32 which are adapted 40 to be clamped to the press cylinder by screws 33.

In mounting the shell by this method, the plate 25 is first secured in place on the cylinder. Then 45 one of the bars with the shell wrapped there-around is secured in place with the bar received in the adjacent groove 26 of the plate 25 as shown in Fig. 8. Then the stretching force is applied to the other bar and the latter finally 50 clamped in place spaced slightly from the groove 26 as shown in Fig. 7.

From the foregoing, it will be apparent that the present invention not only enables a more exact reproduction of the original form to be obtained, 55 but the cost of preparing printing plates and mounting the same in a press is materially reduced. These important results are attained first through the reinforcement of the delicate shell by a thin and flexible filling which may be applied without exposing the shell to a distorting temperature; second through the provision of the present method of and means for securing the thin shell to a supporting surface; third by reinforcement of the shell to enable the detail make-ready to be located directly beneath the shell coating; and fourth by the construction of the plate assembly which permits its use with standard press equipment. 65

The capital investment tied up when the 70 plates are stored for the printing of subsequent issues of a publication is materially reduced in view of the small cost of the filling 7 as compared to the lead backing now generally used and the further fact that the backing plates need not be 75

so stored but may constitute a part of the press equipment. Since the detail make-ready may be made a permanent part of the filled shell, the preparation of new make-readies, as is necessary in present practice preparatory to the printing of a new issue, is also avoided with the present invention. With the non-metallic reinforcing coating preferably employed, reclamation of the shell copper is greatly facilitated.

10 I claim as my invention:

1. The combination with a flexible type-carrying sheet of rectangular shape of metallic flanges rigid with two opposite side edges of said sheet and bent backwardly from the face of the sheet and then reversely and substantially parallel to the sheet, said reversely bent flange portions being formed with longitudinally spaced indentations whereby to stiffen the flanges against bending.
2. The combination with a printing press support having a surface upon which a printing member is to be mounted, of a separately formed expansible plate conforming to the contour of said surface and shiftable edgewise along said support while lying against the same, said plate having parallel marginal edges with fastening devices extending therealong and disposed above the surface of said support, a type-carrying sheet overlying said plate and having fastening elements spaced for engagement with said devices, said plate comprising at least two separate sections cooperating to form a continuous backing for the type on said sheet and abutting each other in edgewise relation and movable relative to each other in one direction while said devices and elements are engaged to expand the plate in an edgewise direction and thereby stretch said sheet over the plate surface to form a unitary printing plate assembly, and means for securing said assembly detachably to the surface of said support while permitting of bodily edgewise ad-

justment of the assembly in any direction along the surface of said support.

3. The combination with a printing press support having a surface upon which a printing member is to be mounted, of a separately formed expansible backing plate conforming to the contour of said surface and shiftable edgewise in any direction while lying against said support, said plate having fastening devices extending along opposite marginal edges and disposed above the surface of said support, a type-carrying sheet overlying said plate and having fastening elements spaced for engagement with said devices, said plate comprising at least two separate sections cooperating when in edgewise abutting relation to form a continuous backing for the type on said sheet and shiftable relatively to each other while said devices and elements are engaged, to expand the plate in an edgewise direction against said elements and thereby stretch said sheet over the plate surface to form a unitary printing plate assembly, and clamping devices on said support overlying the edges of said assembly and acting to fasten said assembly to said support, said clamping devices being detachable to permit of bodily edgewise adjustment of the assembly in any direction along the surface of said support.

4. A printing plate attachable to the surface of a type support of a printing press comprising, in combination, a flexible sheet having type projections and fastening means at opposite edges, and a separately formed expansible backing member underlying said sheet, and means interengaging with said fastening means to stretch the sheet over the member upon expansion of the latter in an edgewise direction, said backing member and type sheet forming a unitary assembly conforming to the contour of said support surface and adjustable in any direction therealong.

ARTHUR B. DAVIS. 40
